[57] **CLAIM**

The ornamental design for a stake puller, as shown and described.

DESCRIPTION

FIG. 1 is a front perspective view of a stake puller showing my new design;

FIG. 2 is a front elevational view thereof;

FIG. 3 is a rear elevational view thereof;

FIG. 4 is a right side elevational view thereof, the left side being a mirror image;

FIG. 5 is a top plan view thereof;

FIG. 6 is a bottom plan view thereof.

The ring and stake have been shown in FIG. 1 for illustrative purposes only and form no part of the claimed design.

FIG. 1

FIG. 2

FIG. 3

FIG. 4

FIG. 5
